HEAT EXCHANGER

William H. Thompson, Chatham, N. J., assignor
to Davis Engineering Corporation, Elizabeth,
N. J., a corporation of Delaware

Application September 19, 1942, Serial No. 458,933

2 Claims. (Cl. 257—238)

The invention herein disclosed relates to a heat exchanger of the kind in which the fluids between which an exchange of heat takes place are not permitted to commingle, such for example, as a heat exchanger in which the heated medium passes through tubes and the medium to be heated is brought into contact with the tubes.

In a heat exchanger of this kind, the continued efficiency of heat transfer from the heating medium to the medium to be heated is dependent upon the cleanliness of the heat transfer surfaces. In oil heaters, for example, the heating medium, steam, is caused to flow through tubes and the oil to be heated is brought into contact with the external surface of the tubes. For increased efficiency in effecting the heat exchange and greater capacity per cubic foot of space occupied by a heat exchanger of this kind, it is desirable that baffles be provided in the heater arranged to cause the oil to be heated to make a number of passes across the heated tubes between the inlet for the oil and the outlet therefor. After use for a comparatively short period, a film and scale deposit upon the heat transfer surface, the outside surface of the tubes. Such deposits reduce the heat conductivity and so the efficiency of the heater.

Generally, as heretofore constructed, it has been necessary, in order to maintain the heat transfer efficiency and capacity of the heater, to dismantle the heater and clean the heat transfer surfaces. It is an object of this invention to provide a heater of this kind in which the heat-transfer surfaces may be mechanically scraped without opening the heater. It is a further object of this invention to provide such a heater with an arrangement whereby the heat-transfer surfaces of the heater may be readily and easily cleaned during the operation of the heater.

These objects and certain advantages that will hereinafter appear are realized in the heat exchanger disclosed in the accompanying drawings. This heat exchanger constitutes one specific embodiment of the invention and it is, with reference to the drawings, described in detail below. The drawings include:

Fig. 1 which is a longitudinal elevation of the heat exchanger;

Fig. 2 which is a transverse section of the same;

Fig. 3 which is a partial, longitudinal section of the same taken on the line 3—3 of Fig. 1; and

Fig. 4 which is a like partial, longitudinal section of the opposite half taken on the line 4—4 of Fig. 1.

The heater illustrated in the drawings includes

5 a cylindrical shell 1 having an end flange 2 at one end and a like end flange 3 at the other end. It is provided adjacent the flange 2, with an inlet opening 4 and a coupling 5 through which a pipe connection may be made with the inlet. Adjacent the other end flange 3, an outlet opening 6 is provided and a coupling 7 through which a pipe connection may be made with the outlet. Intermediate the ends of the shell there is provided 10 a relief connection 8 which communicates with the shell through the opening 9. Couplings 10 and 11 are secured to the shell for connection to columns for supporting the heat exchanger. A drain connection 12, communicating with the shell, is also provided on the lower surface of the shell.

To the end flange 2, there is secured a tube sheet or plate 13. This tube sheet is secured to the flange by bolts 14 extending through the 15 flange 15 of a head 16, the tube sheet and the flange 2. Between the tube sheet and the flange 16, there is a packing ring 17, and a like packing ring 18 is between the tube sheet and the flange 2. The ends of a plurality of tubes 19 (seven in 20 number), are secured in the tube sheet 13 and these tubes extend longitudinally of the shell 1 to a point adjacent the outlet 6. The ends of 25 these tubes, adjacent the outlet 6 are closed, and for a short distance reduced in diameter.

The head 16 forms a chamber 20 between the tube sheet 13 and another tube sheet 21 formed within the head 16. Within the tube sheet 21, the ends of a plurality of tubes 22, seven in number, are secured. Each tube 22 is aligned with a tube 19 and extends into and to the reduced end 30 of the tube 19 in which it is received. Adjacent the end of each tube 22, that is received in and supported by the reduced end of a tube 19, there are provided a plurality of radial openings 23 35 placing the tube 22 into communication with the tube 19. The end of the head 16 is spaced from the tube sheet 21 and forms therewith a steam inlet chamber 24, the end of the head having a tapped opening 25 for the admission of steam to the chamber. A condensate opening 26 40 communicates with the chamber 20, which is also provided with a vent opening 27. Thus, steam admitted through the inlet 25 will pass along tubes 22, through the openings 23 and back along the tubes 19 to the condensate chamber 20 and out through the condensate outlet 26.

Within the shell, there are a plurality of spaced, transverse baffles 28. These baffles are circular disks with a section removed, the edge 29 of which is parallel to a diameter. The baffles are located

between the inlet and outlet openings to the shell and have openings therethrough; through which the tubes 19 extend. Successive baffles are turned through one hundred and eighty degrees and the baffles engage the wall of the shell except at the cut-out section which provides a passage past each baffle. Thus, oil entering the inlet 4 is caused to flow across the tubes, under the baffle 28 adjacent the inlet, again across the tubes and over the next succeeding baffle and so on flowing transversely of the tubes between baffles to the outlet 6.

The several baffles are also provided with openings, four in number angularly spaced through angles of ninety degrees, to receive rods 30. These rods extend through the several baffles and are threaded at each end. At one end, the rods are provided with nuts 31 which engage spacer sleeves 32 between the nuts and the first in the series of baffles. Like spacer sleeves 33 surround the rods between successive baffles. The opposite ends of the rods extend from the last baffle, adjacent the outlet, and through a head or carrier 34. Spacer sleeves 35 surround the rods between the last baffle and the head 34. Nuts 35' on the ends of the rods secure the rods to the head and, through the spacer sleeves, secure the baffles, rigidly, in proper spaced relation.

A spindle 36 is provided with a reduced, threaded end section 37 that extends through an opening therefor provided centrally of the head. The spindle is secured in the head against relative longitudinal movement with respect thereto by a nut 38 threaded on to the reduced end of the spindle. The spindle extends through an end plate 39 secured to the end flange 3 and closing the end of the shell. The end plate is provided with a threaded opening centrally thereof in which the hollow boss 40 of a bracket 41 is received. Through this boss, and a packing gland 42 provided therefor, the spindle 36 extends, and it is slidably in the boss. The end portion of the spindle is provided with a thread 43 that is received in an internally threaded boss 44 rigidly secured in the bracket 41. On the end of the spindle a hand wheel 45 is mounted. As the hand wheel is turned, the spindle is turned and through its threaded connection with the boss 44 moves longitudinally.

The baffles 28 make a scraping fit with the 50 tubes 19 and are movable in the shell. They are

positioned and supported through the rods 30. As the spindle 36 is moved longitudinally as above described, the baffles 28 are moved along the tubes. By so moving the baffles back and forth 5 a short distance, the tubes are scraped clean and thus the heat transfer surfaces of the tubes may be maintained free of deposits and scale which impair the heat conductivity. It will be appreciated that the baffles may be thus moved while 10 the heat exchanger is in operation.

It will be obvious that various changes may be made by those skilled in the art in the details of the embodiment of the invention illustrated in the drawings and described above within the 15 principle and scope of the invention as expressed in the appended claims.

I claim:

1. In a heat exchanger of the kind described, the combination comprising a shell having inlet 20 and outlet openings for the medium to be heated, tubes within the shell extending longitudinally thereof for carrying the heating medium, a plurality of spaced, transverse baffles within the shell between said inlet and outlet openings, the baffles 25 engaging the tubes and the wall of the shell and arranged to cause the medium to be heated to make a plurality of passes transversely of the tubes and being movable longitudinally of the tubes and making a scraping fit therewith, means 30 connecting the several baffles together and arranged to sustain the baffles transverse to the tubes, and means for moving the baffles along the tubes, whereby the baffles scrape the tubes.

2. In a heat exchanger of the kind described, the combination comprising a shell having inlet and outlet openings for the medium to be heated, tubes within the shell extending longitudinally thereof for carrying the heating medium, a plurality of spaced, transverse baffles within the shell between said inlet and outlet openings, the baffles 35 engaging the tubes and the wall of the shell and arranged to cause the medium to be heated to make a plurality of passes transversely of the tubes and being movable longitudinally of the tubes and making a scraping fit therewith, means 40 connecting the several baffles together and arranged to sustain the baffles transverse to the tubes, and means operable externally of the shell 45 for moving the baffles along the tubes, whereby the baffles scrape the tubes.

WILLIAM H. THOMPSON.
